Attorneys

UNITED STATES PATENT OFFICE

SAMUEL JOSEPH BRANSON, OF EVANSTON, ILLINOIS, ASSIGNOR TO THE BRANSON SYSTEM, INC., OF CHICAGO, ILLINOIS, A CORPORATION OF DELAWARE

REINFORCED-CONCRETE SLAB STRUCTURE

Application filed February 1, 1929. Serial No. 336,707.

My invention relates to horizontal concrete construction of a type adapted for floors, ceilings, roofs, and the like, and it has for its object the provision of a new and improved form and arrangement of concrete and cooperating reenforcing parts by reason of which an increased span of such structure may safely be employed without materially increasing the amount or weight of the concrete or the reenforcing steel in proportion to the area as compared with smaller spans heretofore, and without greatly increasing the thickness or depth of the concrete.

To these ends, it is one of the objects of my invention to provide a new and improved distribution of the concrete with respect to the reenforcing bars, whereby at every point a sufficient thickness of concrete is provided for building up the required compressive stresses while at the same time care is taken to prevent the use of concrete in such manner as to increase the dead weight without adequately increasing the strength of the structure.

It is one of the objects of my invention to provide a new and improved arrangement comprising a panel supported by longitudinally extending supports such as beams, partitions, or the like, at its opposite sides, with the marginal portions of the span adjacent to the supports at the sides in the form of plain slabs without auxiliary reenforcing beams extending transversely thereof, the intermediate portion of the panel between the reenforced marginal portions being in the form of a combined slab and beam structure.

It is another object of my invention to provide an improved arrangement in a structure of this type in which reenforcing steel bars extend continuous substantially from the beam or other support at one side of the panel or section to the beam at the opposite side, serving effectively as the bottom tension bars for the beams at the intermediate combination slab and beam portion of the span and also serving effectively for building up bottom compressive stresses for the beamless slab structure portion adjacent to the outside beams or other supports.

It is one of the objects of my invention to provide a construction in which a horizontal

concrete structure is supported from beams at its four sides, with the central portion of the span arranged to support its normal load partially from the beams and partially from the marginal portions of the span, and with said marginal portions of the span adjacent to the beams at the sides of the span of different arrangement and reinforced more strongly for supporting from the beams both their own load and a portion of the load carried by the intermediate portion of the span. It is one of my objects to provide a structure of this type in which the effective thickness of the slab portion of the structure is decreased by steps from a point adjacent to the side beam to the point of inflection, whereby the use of surplus and ineffective concrete at the central portion of the span shall be avoided.

It is another object of my invention to provide an improved arrangement of parts comprising two concrete slab portions of different thickness formed integrally with each other, with a reenforcing bar extending along the edge of the thicker slab portion substantially at its bottom face, being held in position by a pad or rib of concrete formed integrally with the slab portion, whereby substantially the full thickness of the thicker slab portion serves to build up effective diagonal tension and compression stresses respectively in connection with said reenforcing bar.

It is another object of my invention to improve constructions of this type in sundry details hereinafter pointed out. The preferred means by which I have accomplished my several objects are illustrated in the drawing and are hereinafter specifically described. That which I believe to be new and desire to cover by Letters Patent is set forth in the claims.

In the drawing,—

Fig. 1 is a top plan view of a quadrilateral section of a floor embodying the preferred form of my improvements, with one corner broken away, and showing fragmentary portions of the adjacent sections;

Fig. 2 is a vertical sectional view, taken

substantially at line 2—2 of Fig. 1, being shown upon an enlarged scale;

Figs. 3 and 4 are vertical sectional views taken at the lines 3—3 and 4—4 respectively 5 of Fig. 2; and

Fig. 5 is a vertical sectional view taken at line 5—5 of Fig. 1.

Referring to the several figures of the drawing, in which corresponding parts are 10 indicated by the same reference characters,— 10, 11, 12 and 13 indicate upright supports of any approved type arranged in quadrilateral spaced relation with respect to each other. Between the supports at each of the 15 four sides of the section, I have provided comparatively deep beams 14 of any approved type supported at their ends from the columns 10, 11, 12 and 13. The space between the beams 14 is bridged by a concrete 20 slab structure comprising a plurality of slab portions of different forms as hereinafter set forth, such several slab portions being formed integrally with each other and extending continuous over the beams so as to 25 provide with the adjacent sections a cantilever construction.

In the construction shown, each of the upright supports is in the form of a concrete column reenforced by steel placed in position 30 progressively as the pouring of the concrete proceeds, as distinguished from a steel skeleton construction employing structural shapes, but my invention is not limited to this particular type of column. Each of the 35 beams 14 in the construction shown is reenforced by a horizontally disposed I-beam 15, and a plurality of reinforcing bars 16 of any approved type and disposed in any desired arrangement, but the beams may be 40 otherwise formed and reenforced if desired.

In the construction shown, I have employed marginal slab portions 17 of substantial thickness or depth at the sides adjacent to the beams 14 such slab portions being 45 formed integrally with the beams. Inside of the thick marginal portions 17, I have provided slab portions 18 of decreased thickness or depth formed integrally with the slab portions 17, and between the slab portions 50 18 I employ a combination slab and beam structure 19, of which the beam portions are indicated by numerals 20 and the slab portions by numerals 21.

For reenforcing the intermediate slab and 55 beam structure and for supporting it from the beams 14, I have provided top tension bars 22 at each side of the section, said bars extending across the beams 14 in spaced relation to each other adjacent to the top face 60 of the floor, being placed preferably at the minimum depth necessary for effective fireproofing. These reenforcing bars extend inwardly some little distance to or a short distance beyond the point of inflection of the 65 cantilever structure. I provide also positive

tension bars 23 extending across the slab portions 18 at substantially the bottom faces of such slab portions, such bars being held in position with respect to the slab portions 18 by means of pads 24 of concrete formed 70 integrally with said slab portions 18, such pads surrounding the bars 23 and serving to bond them securely to the slab. The bars 23 extend in one direction from the slab portions 18 into and through the slab portions 75 17 and into the beams 14, and extend in the opposite direction into and along the bottom portions of the beam portions 20 of the combination slab and beam structure 19.

By the provision of the comparatively thick 80 slab portions 17 and the bars 23 which serve at these points as negative compression members, diagonal tension is built up to an adequate degree. By the use of the top tension bars 22 extending to or beyond the points of 85 inflection, the slab portions 18 are supported strongly enough to take care of the load imposed upon them. By the use of the reenforcing bars 23 in crossed relationship in the slab and beam structure, serving as bottom tension bars for the beams 20 of such slab and beam structure, the central portion of the span is afforded ample support from the thicker slab portions 18 and the beams 14 regardless of the fact that the slab portions 95 21 are made comparatively thin.

By the use of my improved construction, I have provided the requisite strength and stiffness for supporting a span of twenty-one 100 or twenty-two feet between lines of centers, with the intermediate slab portion not more than about three inches in thickness and with the complete thickness or depth of the beams of the combination slab and beam structure 105 not more than about six inches.

While I prefer to employ a construction substantially in conformity to that shown in my drawing, it is to be understood that my invention is not to be limited thereto except so far as the claims may be so limited by the 110 prior art.

I claim:—

1. In a reenforced and fireproofed concrete structure, the combination of two longitudinally extending supports in spaced relation to each other, a slab of concrete extending out from each support toward the other, a reenforcing bar extending substantially from one support to the other substantially at the bottom faces of the slab portions, pads of concrete formed integrally with said slab portions surrounding said reenforcing bar serving to bond said bar with the slab portions, a concrete beam extending across from one of said slab portions to the other surrounding said reenforcing bar at its lower portion and with its upper face flush with the upper faces of said slab portions, and means formed integrally with said slab portions 115 and said beam at opposite sides of the beam 120

125

130

bridging the space between said first named slab portions.

2. In a reenforced and fireproofed concrete structure, the combination of two longitudinally extending supports in spaced relation to each other, a plurality of reenforcing bars extending in spaced relation to each other substantially from one support to the other, a slab of concrete extending out from each support above said reenforcing bars with the bars located substantially at the bottom faces of the slab portions, pads of concrete formed integrally with said slab portions surrounding said reenforcing bars serving to protect said bars and to bond them with said slab portions, concrete beams extending across from one slab portion to the other flush at their upper faces with the upper faces of the slab portions and surrounding said reenforcing bars at their lower portions, and slab portions bridging from one beam to the next between said first named slab portions, said second named slab portions being of decreased thickness as compared with said first named slab portions.

3. A reenforced concrete structure comprising in combination a slab of concrete, a combination slab and beam structure formed integrally with said first named slab, with the second named slab and beam portions merged into said first named slab, said first named slab being of greater depth than the second named slab portion, a reenforcing bar extending along the edge of said first named slab portion at substantially the bottom face of said first named slab, and a pad of concrete formed integrally with said first named slab on its bottom face surrounding said reenforcing bar serving to protect the bar and to bond it to said slab.

4. A reenforced concrete structure, comprising in combination two slab portions of different thickness formed integrally with each other with their top faces flush, a reenforcing bar extending along the edge of the thicker slab portion substantially at the bottom face thereof, and a pad of concrete formed integrally with said thicker slab portion on its bottom face surrounding said reenforcing bar and holding it in fixed position with respect to said slab.

5. A reenforced concrete structure, comprising in combination two slab portions of different thickness formed integrally with each other with their top faces flush, a reenforcing bar extending along the edge of the thicker slab portion substantially at the bottom face thereof, a pad of concrete formed integrally with said thicker slab portion on its bottom face surrounding said reenforcing bar and holding it in fixed position with respect to said slab, and a plurality of top tension bars in the top surface portion of said combined slab structure at substantially right

angles with respect to said first named reenforcing bar.

6. A reenforced concrete structure, comprising in combination two slab portions of different thickness formed integrally with each other with their top faces flush, a reenforcing bar extending along the edge of the thicker slab portion substantially at the bottom face thereof, a plurality of bottom tension bars at substantially the bottom face of said thicker slab portion at substantially right angles with respect to said first named reenforcing bar, and pads of concrete formed integrally with said thicker slab portion on its bottom face surrounding said reenforcing bars and holding them in fixed position with respect to the slab.

7. A reenforced concrete structure, comprising in combination two slab portions of different thickness formed integrally with each other with their top faces flush, a reenforcing bar extending along the edge of the thicker slab portion substantially at the bottom face thereof, a plurality of top tension bars in the top surface portion of said combined slab structure at substantially right angles with respect to said first named reenforcing bar, a plurality of bottom tension bars at substantially the bottom faces of said thicker slab portion at substantially right angles with respect to said first named reenforcing bar, and pads of concrete formed integrally with said thicker slab portion on its bottom face surrounding said reenforcing bars and holding them in fixed position with respect to the slab.

8. A reenforced concrete structure, comprising in combination two slab portions of different thickness formed integrally with each other with their top faces flush, a reenforcing bar extending along the edge of the thicker slab portion substantially at the bottom face thereof, a plurality of bottom tension bars at substantially the bottom face of said thicker slab portion at substantially right angles with respect to said first named reenforcing bar, pads of concrete formed integrally with said thicker slab portion on its bottom face surrounding said reenforcing bars and holding them in fixed position with respect to said slab, and beams formed integrally with said thinner slab and comprising portions thereof and merged at their ends with the edge of said thicker slab, said bottom tension bars being surrounded by said beams at their lower portions.

9. A reenforced concrete structure, comprising in combination two slab portions of different thickness formed integrally with each other with their top faces flush, a reenforcing bar extending along the edge of the thicker slab portion substantially at the bottom face thereof, a plurality of top tension bars in the top surface portion of said combined slab structure at substantially right

angles with respect to said first named re-enforcing bar, a plurality of bottom tension bars at substantially the bottom face of said thicker slab portion at substantially right angles with respect to said first named re-enforcing bar, pads of concrete formed integrally with said thicker slab portion on its bottom face surrounding said reenforcing bars and holding such bars in fixed position with respect to the slab, and beams formed integrally with said thinner slab portion and comprising portions thereof and merged at their ends with the edge of said thicker slab portion, said bottom tension bars being surrounded by said beams at their lower portions.

10. A reenforced concrete structure comprising in combination a slab of concrete, a combination slab and beam structure formed integrally with said first named slab, with the second named slab and beam portions merged into said first named slab, said first named slab being of greater depth than the second named slab portion, a reenforcing bar extending across said thicker slab portion at substantially the level of the bottom face of said slab portion and extending into and along the lower portion of one of said beams, and a pad of concrete formed integrally with said thicker slab portion on its bottom face surrounding said reenforcing bar.

11. A reenforced concrete structure comprising in combination a slab of concrete, a combination slab and beam structure formed integrally with said first named slab, with the second named slab and beam portions merged into said first named slab, said first named slab being of greater depth than the second named slab portion, a reenforcing bar extending along the edge of said first named slab portion at substantially the bottom face of said first named slab, a second reenforcing bar extending across said first named slab portion and extending into and along the lower portion of one of said beams at substantially the bottom face of said first named slab portion, and pads of concrete formed integrally with said first named slab portion on its bottom face surrounding said reenforcing bars and bonding them to said slab portion.

12. A reenforced concrete structure comprising in combination a slab of concrete, a combination slab and beam structure formed integrally with said first named slab, with the second named slab and beam portions merged into said first named slab, said first named slab being of greater depth than the second named slab portion, a reenforcing bar extending along the edge of said first named slab portion at substantially the bottom face of said first named slab, a series of reenforcing bars extending across said first named slab portion and extending into and along the lower portions of said beams at sub-

stantially the level of the bottom face of said first named slab portion, and pads of concrete formed integrally with said first named slab portion on its bottom face surrounding said reenforcing bars and merging at their ends with said beams.

13. A reenforced concrete structure comprising in combination a slab of concrete, a second slab of concrete of decreased thickness formed integrally with said first named slab, a third slab of concrete of still smaller thickness formed integrally with said second slab, a reenforcing bar extending along the edge between said second and third slabs substantially at the bottom face of the second slab, and a pad of concrete formed integrally with said second slab surrounding said reenforcing bar serving to bond said bar to said slab.

14. A reenforced concrete structure comprising in combination a slab of concrete, a second slab of concrete of decreased thickness formed integrally with said first named slab, a combination slab and beam structure of concrete formed integrally with said second slab with the beams merging at their ends into said second slab and of substantially the same depth as that of the first named slab and with the slab portion of said combination slab and beam structure of smaller depth than that of the second slab, reenforcing bars extending across the bottom face of said second slab at substantially the bottom face thereof and extending in one direction into said first named slab and in the other direction into and along said beams, and pads formed integrally with said second slab surrounding said reenforcing bars.

15. A reenforced concrete structure comprising in combination a slab of concrete, a second slab of concrete of decreased thickness formed integrally with said first named slab, a combination slab and beam structure of concrete formed integrally with said second slab with the beams merging at their ends into said second slab and of substantially the same depths as that of the first named slab and with the slab portion of said combination slab and beam structure of smaller depth than that of the second slab, reenforcing bars extending across the bottom face of said second slab at substantially the bottom face thereof and extending in one direction into said first named slab and in the other direction into and along said beams, a reenforcing bar extending along the edge between said second and third slab portions substantially at the bottom face of said second slab, and pads formed integrally with said second slab surrounding said reenforcing bars and serving to bond said bars to said slab.

16. A reenforced concrete structure comprising in combination a reenforced concrete beam, slabs of concrete connected with said

- beam at its opposite sides, combination slab and beam structures connected with said first named slabs, with the beam portions extending toward said first named beam and with 5 the slab portions of smaller depth than that of the first named slabs, reenforcing bars extending across said first named slabs at substantially their bottom faces and extending into and along the beams of said slab and beam structures, reenforcing bars at opposite sides of 70 said first named beam extending along the edges between the first mentioned slabs and the slab and beam structures at substantially the bottom faces of the first mentioned slabs, and pads formed integrally with said first 75 named slabs and surrounding said reenforcing bars serving to bond said bars to said slabs.
17. A reenforced concrete structure comprising in combination a reenforced concrete beam, slabs of concrete connected with said beam at its opposite sides, combination slab and beam structures connected with said first named slabs, with the beam portions extending 20 toward said first named beam and with the slab portions of smaller depth than that of the first named slabs, top tension bars extending across said first named beam and into and across said first named slabs into the 25 slab and beam structures adjacent to their upper faces, other reenforcing bars extending across said first named slabs at substantially their bottom faces and extending into and along the beams of said slab and beam structures, and pads formed integrally with said first 30 named slabs surrounding said reenforcing bars serving to bond them to said slabs.
18. A reenforced concrete structure comprising in combination a reenforced concrete beam, slabs of concrete connected with said beam at its opposite sides, combination slab and beam structures connected with said first named slabs, with the beam portions extending 35 toward said first named beam and with the slab portions of smaller depth than that of the first named slabs, reenforcing bars extending across said first named slabs at substantially their bottom faces and extending into and along the beams of said slab and beam structures, 40 and pads formed integrally with said first named slabs and surrounding said reenforcing bars serving to bond said bars to said slabs.
19. A reenforced concrete structure comprising in combination a reenforced concrete beam, slabs of concrete connected with said beam at its opposite sides, combination slab and beam structures connected with said first named slabs, with the beam portions extending 45 toward said first named beam and with the slab portions of smaller depth than that of the first named slabs, reenforcing bars at opposite sides of said first named beam extending along the edges between the first mentioned slabs and the slab and beam structures at substantially the bottom faces of the first mentioned slabs, and pads formed integrally with said first 50 named slabs and surrounding said reenforcing bars serving to bond said bars to said slabs.
20. A reenforced concrete structure comprising in combination a reenforced concrete beam, slabs of concrete connected with said beam at its opposite sides, combination slab and beam structures connected with said first named slabs, with the beam portions extending 55 toward said first named beam and with the slab portions of smaller depth than that of the first named slabs, top tension bars extending across said first named beam and into and across said first named slabs into the slab and beam structures adjacent to their upper 60 faces, other reenforcing bars extending across said first named slabs at substantially their bottom faces and extending into and along the beams of said slab and beam structures, reenforcing bars at opposite sides of 70 said first named beam extending along the edges between the first mentioned slabs and the slab and beam structures at substantially the bottom faces of the first mentioned slabs, and pads formed integrally with said first 75 named slabs and surrounding said reenforcing bars serving to bond said bars to said slabs.
